Letters Patent No 2220 Dated Nov. 14. 1865

1 Design for a Trade mark.

The Schedule referred to in these Letters Patent and making part of the same.

To all whom it may concern:

Be it known that I Martin Seippe, of Lancaster, in the County of Lancaster and State of Pennsylvania, have originated and designed a new pattern for a brand, to be burned on Sugar Boxes for a trade mark, of which the following is a full, clear, and exact description, reference being had to the accompanying drawings, making a part of this specification. The drawing shows the Brand forming the words or letters "The Park Havana" in two curved lines, upon the oval plate, for a Trade mark, as shown by the drawing, the form and position of the letters, without respect to the outer border or central filling between said letters.

What I claim and desire to secure by Letters Patent is the design for a brand or trade mark as shown and set forth.
